UNITED STATES PATENT OFFICE.

TIMOTHY C. MANNING, OF OMAHA, NEBRASKA.

GRAIN WASHER AND DRIER.

Application filed February 11, 1927. Serial No. 167,485.

This invention relates to a machine for cleaning and drying grain and more particularly to a machine adapted to remove dirt, smut spores, nematode gall dust and other injurious substances from wheat berries and thereby prepare the same for the subsequent operations of milling the grain into flour.

The principal object of this invention is to provide a machine of this character which will moisten, thoroughly clean and dry the wheat with a minimum addition to the water content of the wheat berries, and in which the percentage of water added can be accurately controlled.

A further object is to provide a simple, efficient and inexpensive machine of this character which thoroughly cleans a continuous flow of grain passing through the same.

20 A further aim is to provide means for uniformly moistening the stream of wheat flowing into the machine, and uniformly clean and dry the same, thereby providing wheat of uniform quality in these respects.

25 In the accompanying drawings:

Figure 1 is a vertical longitudinal section of a machine embodying my invention showing portions thereof broken away. Figure 2 is a vertical transverse section taken on line 2—2, Fig. 1. Figure 3 is a vertical transverse section taken on line 3—3, Fig. 1. Figure 4 is a vertical longitudinal sectional view of the grain moistening chute. Figure 5 is an end view thereof showing a portion broken away. Figure 6 is an end view, on a reduced scale, of the grain cleaning and drying machine.

The moistening, cleaning and drying mechanism is supported on a frame which may be 40 of any well known and approved construction and as shown in the drawings comprises four upright legs or standards 7; upper end cross bars 8 preferably made of two angle bars riveted to opposite sides of fish plates 45 9 which connect the legs and these bars; a lower cross bar 10; upper longitudinal bars 11 and lower longitudinal bars 12 secured at their ends to the legs 7, and suitable bracing bars 13 between the legs and the lower longitudinal bars 12.

Within this frame are arranged a foraminous cleaning cylinder 14 of relatively small diameter, and a coaxial foraminous drying cylinder 15 of relatively large diameter, these cylinders being supported on the lower longitudinal frame bars 12 by an intermediate head 16, an end head 17 arranged at the outer end of the smaller cleaning cylinder 14, and an end head 18 supporting the outer end of the larger drying cylinder 15. Each of these 55 heads is preferably of circular form and is provided with integrally cast legs 19 which are bolted to the upper side of the lower longitudinal frame bars 12 in the case of the heads 16 and 18 and to the lower cross bar 10 in the case of the head 17.

The foraminous drying cylinder 15 as shown in the drawings is composed of five sections or segments each of which comprises a curved perforated plate 20, to the longitudinal edges of each of which angle irons 22 are secured, the corresponding angle irons of the section being adapted to be bolted together, and draw the several sections against annular beads 23 formed on the inner side of 75 the end head 18 and the opposing side of the intermediate head 16. These two cylinder heads 16 and 18 are preferably rigidly secured together by tie rods 24 arranged exteriorly of the cylinder sections.

The cleaning drum is composed of a similar number of cylinder sections 25 similarly supported within a plurality of annularly disposed tie rods 26 upon annular beads 27 provided on the heads 16 and 17. These cylinder sections 25 are not, however, perforated their entire extent, but are perforated only at their inner ends, the outer ends forming an imperforate cylinder 28 for a purpose which will presently appear, and each of the 90 angle bars 29 by which the several sections are bolted together are spaced from the outer surface of each cylinder section by a filler bar 30, thereby forming inwardly opening channels or guideways 31 at the opposite longitudinal edges of each section. These guideways receive the opposite edges of curved slides 33 which extend across the outer surface of each section and are readily slideable by means of handles 34 so as to cover any 95 100

desired portion of the inner perforated end of the section, and thereby adjustably vary the effective area of the cylinder.

The moistened grain is introduced into the cleaning cylinder through a grain inlet opening 35 provided in the end head 17, and is thence carried through the cleaning cylinder and through a triangular opening 36 provided in the upper part of the intermediate cylinder head 16 into the drying cylinder 15. The cleaned grain is carried through the drying cylinder, and when completely dried is discharged through a discharge opening 37 provided in the end head 18, the grain being directed into a suitable chute or conveyer (not shown) by a spout 38.

The mechanism within the foraminous cylinders for cleaning, drying and conveying the moistened grain is carried by a longitudinal shaft 40 which is journaled in ball bearings 41, which bearings are bolted to the upper sides of the upper transverse frame bars 8. This shaft may be driven in any suitable manner as by a pulley 42. On this shaft within the cleaning cylinder is arranged a drum 43 composed of end heads 39 having a plurality of radially outwardly projecting spaced lugs 44, and a sheet metal cylinder 45 secured between these heads. On this drum are obliquely mounted a plurality of vanes or blades 46 which extend the entire length of the drum and are adapted to engage the moist grain at the bottom of the cylinder, and carry it around the inner surface of the cleaning cylinder and also move it toward the intermediate head 16 and into the drying cylinder. For this purpose the blades 46 are S-shaped and are formed to conform to the curvature of the drum, and are secured at their ends in any suitable manner to the spaced lugs 43 provided on each of the drum heads. These blades are preferably given substantial pitch to ensure proper conveying of the moist grain along and around the cleaning drum, and the spaced lugs 44 are preferably provided in such numbers as to permit of accommodating additional blades should this become necessary or desirable in operating on any particular kind of grain. The outer edge of each of the blades is arranged close to the inner surface of the cylinder, and the moist grain is forced around the perforated surface thereby loosening the dirt, smut, gall dust and other impurities which are forced out through the perforations and drop from the cylinder. The grain, while being carried around the cylinder, is also shifted lengthwise thereof toward the intermediate head 16, where it is elevated by the inner extremities of the blades and passes through the triangular opening 36 in the upper part of the intermediate head 16 and into the inner end of the drying cylinder 15.

Within the drying cylinder a drum is mounted on the shaft 40, this drum being

larger than the drum 47 in the cleaning cylinder and being composed of similar end heads 48 having outwardly extending spaced lugs 49 and a central cylindrical section 50 secured to the end heads. To these lugs 49 are suitably secured bars 51 which extend longitudinally of the drum and preferably extend beyond the ends of the same. Each of these bars is formed with a plurality of outwardly projecting beaters or wings 52 which are arranged obliquely relative to the line of travel and the outer edges of these beaters are arranged close to the inner surface of the foraminous cleaning cylinder. By reason of the greater diameter of this drum, the beaters travel at a higher speed than the blades or vanes of the cleaning drum and consequently upon engaging the grain, throw the grain forcibly against the inner surface of the drum, and rapidly carry it around the inner surface of the same thereby beating and forcing any remaining moisture out of the grain and through the perforations in the cylinder. By reason of the oblique arrangement of the beaters, the grain is also shifted longitudinally along the cylinder and finally discharged through the discharge spout 38.

Means are provided for uniformly moistening the grain before it passes into the cleaning cylinder, which means permit of accurately controlling the amount of water added and are preferably constructed as follows:

At the inlet end of the machine is mounted a vertical chute 53 having an open upper end 54 adapted to receive uncleaned grain from any suitable source and an inclined lower end 55 which discharges into the grain inlet opening 35 in the end head 17 of the cleaning cylinder. This chute is preferably square in cross section and alternately on opposite sides are mounted a plurality of inwardly extending, inclined baffles or shelves 56 which force the stream of grain to take a staggered path through the chute, the grain being alternately deflected from side to side by the alternating baffles. Immediately below the lower or inner end of the uppermost baffle 56, a water pipe 57 passes through the chute, and this water pipe is connected to a similar horizontal water pipe 58 passing through the chute immediately below the next lower baffle by a vertical pipe 59. The lower water pipe is capped and water under pressure is supplied to these pipes from a main 60, the amount of water supplied being controlled by a valve 61.

Each of these pipes is provided with a longitudinal upper row or series of ports 62 which extend upwardly at an angle and are adapted to direct sprays of water against the underside of the stream of wheat flowing over the lower end of the baffle, and a lower row of ports 63 which direct sprays of water against the upper side of the stream of wheat

flowing over the next lower baffle. By this means the grain is thoroughly moistened on all sides two successive times and the wheat is uniformly moistened throughout.

5 The addition of water can be accurately regulated by the valve 61, and the amount of water taken out can be regulated by shifting the slides 33 so as to cover a greater or lesser extent of the perforated area of the cleaning 70 cylinder and thereby decrease or increase its effective draining capacity, the effective extent of the perforated area being, in all positions of the slides or shutter, sufficient to remove all of the smut, gall dust, dirt and 15 other impurities from the grain. This control of both the addition and the removal of the water permits of interregulation at both ends of the process and consequently securing the optimum result. In actual practice this machine will moisten, clean and dry smutty and dirty grain with the addition of less than one-half of one per cent to the water content thereof.

To completely enclose and guard the 25 washing and drying mechanism, a sectional sheet metal casing is provided which includes end walls 65 suitably secured to the end frame bars and reinforced by suitable angle irons, two upper curved sections 66 connected 30 by hinges 67 and resting on the upper side of the reinforced end walls 65, removable curved panels 68 resting on the upper longitudinal frame bars 11 and the end walls 65 and held by latches 69 against the upper 35 hinged sections 66, and vertical panels 70 removably secured to and closing the spaces between the upper and lower longitudinal frame bars 11 and 12.

The under side of the mechanism is enclosed by a pair of horizontal troughs 71 which receive the water and impurities which fall from the foraminous drying and cleaning cylinders. Preferably two of such troughs are provided and each comprises inclined sheet metal side walls 72 which are connected at their lower ends to a bottom portion 73 which is semi-circular in cross section and contains a conveying screw 74. The corresponding upper ends of the troughs are joined together to form a central apex, and the outer edges thereof are suitably secured to the longitudinal frame bars 11, and the ends of each trough are closed by the end walls 65 and braced by a cross bar 75. The 55 conveying screws 74 are adapted to move the impurities lengthwise of the trough and as shown comprise longitudinal shafts 76 journaled in suitable bearings at the ends of the troughs and carrying the usual convolute screw blades 77. Each of these shafts is turned by a sprocket 78 arranged at the intake end of the machine which is driven from a sprocket wheel 79 mounted on the main shaft 40 by an endless drive chain 80 passing 60 around the three sprockets and held taut by

a suitable belt tightener 81, although any other suitable driving means may be provided. Each of the screws is adapted to convey the impurities toward the discharge end of the machine where the same pass through discharge outlets 82.

As a whole this invention is very simple in construction and operation considering the function which it performs and it operates to thoroughly and uniformly moisten, clean and 75 dry the grain with a minimum addition to the water content thereof.

I claim as my invention :

1. In a machine of the character described, a foraminous cleaning cylinder receiving the 80 grain, a foraminous drying cylinder arranged coaxially of said cleaning cylinder, a shaft extending through said cylinder, a plurality of obliquely disposed vanes carried by said shaft and extending substantially the 85 full length of said drying cylinder, said vanes being adapted to carry the grain around the inner surface of said cylinder and also move it longitudinally into said drying cylinder, a plurality of obliquely disposed beaters carried by said shaft, said beaters being adapted to engage the grain and shift it longitudinally along the drying cylinder, and means for discharging the cleaned and dried grain 90 from said drying cylinder.

2. In a machine of the character described, a foraminous cleaning cylinder provided with a grain intake opening, a coaxially disposed foraminous drying cylinder, a head interposed between the corresponding ends of 100 said cylinders, said head having an opening in its upper part, a shaft extending through said cylinders, a plurality of obliquely disposed vanes carried by said shaft and extending substantially the full length of said cleaning cylinder, said vanes being adapted to carry the grain around the inner surface of said cleaning cylinder and also move it longitudinally through said opening into said drying cylinder, a plurality of obliquely disposed 105 beaters carried by said shaft, said beaters being adapted to engage the grain and shift it longitudinally along the drying cylinder, and means for discharging the cleaned and dried grain 110 from said drying cylinder.

3. In a machine of the character described, a foraminous cleaning cylinder, a foraminous drying cylinder, a head interposed between the corresponding ends of said cylinders, said head having an opening in its upper part, a head arranged at the outer end of said cleaning cylinder and provided with a grain intake opening, a head arranged at the outer end of said drying cylinder and provided with a grain discharge opening, a drum 120 rotatably mounted in said grain cleaning cylinder, a plurality of obliquely disposed vanes carried by said drum and extending substantially the full length thereof, said vanes being adapted to carry the grain around the in- 125

ner surface of said cleaning cylinder and also move it longitudinally through the opening of said intermediate head into said drying cylinder, a second drum rotatably mounted in said drying cylinder, and a plurality of obliquely disposed beaters mounted on said last named drum, said beaters being adapted to engage the grain and shift it longitudinally along said drying cylinder through said discharge opening.

4. In a machine of the character described, a foraminous cleaning cylinder of relatively small diameter, a foraminous drying cylinder of relatively large diameter, a shaft extending through said cylinders, a relatively small drum mounted on said shaft within said cleaning cylinder, a relatively large drum mounted on said shaft within said drying cylinder, means for feeding moistened grain into said cleaning cylinder, vanes carried by said small cylinder, said vanes being adapted to carry the grain around the inner surface of said cleaning cylinder and also shift it longitudinally into said drying cylinder, beaters carried by said large drum, and means for discharging the grain from the drying cylinder.

5. In a machine of the character described, means for moistening the grain, a foraminous cleaning cylinder receiving the moistened grain, rotatable means arranged in said cylinder for carrying said grain around the inner surface of said cylinder, and means for adjustably covering a portion of said cylinder for varying its effective extent.

6. In a machine of the character described, means for moistening the grain, a cylinder receiving the moistened grain, one end of said cylinder being foraminous and the other end imperforate, rotatable means arranged in said cylinder for carrying the grain around the inner surface of said cylinder, and means for varying the effective extent of the foraminous portion comprising a shutter longitudinally movable over said imperforate and foraminous portions.

7. In a machine of the character described, means for moistening the grain, a cylinder receiving the moistened grain and including a number of sections one end of each of which sections is foraminous at one end and imperforate at the other and is formed at its edges to provide channels, rotatable means arranged in said cylinder for carrying the grain around the inner surfaces of said sections, and means for varying the effective extent of the foraminous portions of said sections including shutters having their opposite edges arranged in said channels, and said shutters being longitudinally movable over said imperforate and foraminous portions.

8. A machine of the character described, including a foraminous cleaning cylinder receiving the grain to be cleaned, a foraminous

dryer cylinder, said cylinders being arranged end to end and being coaxially disposed, a shaft extending longitudinally through said cylinders, a plurality of obliquely disposed vanes carried by said shaft and extending substantially the full length of said cleaning cylinder, said vanes cooperating with said cleaning cylinder to shift the grain longitudinally into said drying cylinder, and a plurality of beaters carried by said shaft and arranged within said drying cylinder, said beaters being adapted to shift the grain longitudinally along said drying cylinder and discharge it therefrom.

9. A machine of the character described, including a foraminous cleaning cylinder receiving the grain to be cleaned, said cleaning cylinder being of relatively small diameter, a foraminous drying cylinder of relatively large diameter, said cylinders being arranged end to end and being coaxially disposed, a shaft extending longitudinally through said cylinders, a plurality of obliquely disposed vanes carried by said shaft and extending substantially the full length of said cleaning cylinder, said vanes cooperating with said cleaning cylinder to shift the grain longitudinally into said drying cylinder, and a plurality of beaters carried by said shaft and arranged within said drying cylinder, said beaters cooperating with said drying cylinder to shift the grain longitudinally therefrom.

10. A machine of the character described, including a foraminous cleaning cylinder, a foraminous drying cylinder, said cylinders being arranged end to end and being coaxially disposed, an end head for each of said cylinders, an intermediate head between said cylinders, a shaft extending longitudinally through said cylinders, a grain inlet in the end head of said cleaning cylinder, a transfer opening in the upper part of the intermediate head and a grain outlet in the end head of said drying cylinder, obliquely disposed vanes carried by said shaft and extending substantially the full length of said cleaning cylinder, said vanes being adapted to shift the grain longitudinally along said cleaning cylinder and through said transfer opening, and a plurality of beaters carried by said shaft and cooperating to shift said grain along said drying cylinder and through said outlet.

11. In a machine of the character described, a foraminous cleaning cylinder, a foraminous drying cylinder, a head interposed between the corresponding ends of said cylinders, said head having an opening, a head arranged at the outer end of said cleaning cylinder and provided with a grain intake opening, a head arranged at the outer end of said drying cylinder and provided with a grain discharge opening, rotatable

conveying means arranged in said cleaning cylinder and cooperating to carry the grain around the inner surface of said cleaning cylinder and also to move it longitudinally through the opening in said intermediate head into said drying cylinder, and rotatable beating means rotatably mounted in said dry-

ing cylinder, said beating means cooperating to engage the grain and shift it longitudinally along said drying cylinder through said discharge opening.

In testimony whereof I hereby affix my signature.

TIMOTHY C. MANNING.
